UNITED STATES PATENT OFFICE.

HARRY E. NORWOOD AND FREDERICK G. MAIER, OF NEW YORK, N. Y., ASSIGNEES, BY
MESNE ASSIGNMENTS, TO PERFECT WINDOW REGULATOR CORPORATION, OF LONG
ISLAND CITY, NEW YORK, A CORPORATION OF DELAWARE.

WINDOW REGULATOR.

Application filed January 11, 1922. Serial No. 528,585.

To all whom it may concern:

Be it known that we, HARRY E. NORWOOD and FREDERICK G. MAIER, citizens of the United States, and residents of New York, in the county of New York and State of New York, have invented certain new and useful Improvements in Window Regulators, of which the following is a specification.

10 Our invention relates to window regulators adapted to raise or lower windows, and it is particularly adapted for use with that type of regulators now well known and employing two sprockets or wheels, a chain or other linear member running over said sprockets or wheels, means for rotating said sprockets and a connection between the chain and the window whereby the window may be raised or lowered as desired upon rotation of the 20 rotating means in the proper direction.

The object of the invention is the provision of a device which may be cheaply constructed and easily manufactured and which will automatically adjust itself at all times 25 to keep the chain or other linear member taut and thereby prevent it from running off the sprockets under abnormal conditions.

A further object of the invention is the 30 mounting of the regulator in position by novel means which will permit it to be bodily and easily removed without removal of the side of the door or other portion forming a wall of the window well.

In the accompanying drawing illustrating 35 a practical embodiment of the invention:

Fig. 1 is a side elevation of the window regulator as applied to a window.

Fig. 2 is an enlarged side elevation (partly broken away) of the lower portion of the 40 regulator.

Fig. 3 is a vertical cross-section on the line 3—3 of Fig. 2.

Fig. 4 is a horizontal section on the line 4—4 of Fig. 2.

Fig. 5 is a front elevation of the slide member.

Fig. 6 is an end view of the bolt on which the lower sprocket is mounted.

Fig. 7 is a horizontal section on the line 7—7 of Fig. 5.

Referring in detail to the several figures of the drawing:

1 indicates a window which is reciprocated vertically in a suitable frame the lower part of which is indicated at 2. 3 indicates a plate secured to the lower part 2, said plate having an upper sprocket 4 mounted thereon. A vertical depending bar or strap is indicated at 5, the lower end of said bar being provided with bevelled edges 6. The base 7 of the window well has a bracket or support 8 secured thereto by any suitable means as by the screws as shown, which bracket is provided with a slot 9 the top of the wall thereof being rounded or curved as at 10. The lower end of the bar 5 is received by the slot 9 of the bracket 8 and is loosely held therein while the upper end of said bar is fastened as by the screws or rivets 11 to the plate 3. This manner of mounting and 60 loosely holding the bar in the window well is particularly desirable as it permits the installation or removal of the device without tearing down a side wall of the window well or the upholstery of the door as is necessary 65 in most cases in order to fasten the lower end of the bar within the window well. In the present construction the bar is merely slipped within the window well and inserted 70 in position within the slot by "feeling", the bevelled edges 6 of said bar and the rounded portion 10 of the bracket 8 considerably 75 facilitating the proper positioning of the bar within the slot in an obvious manner.

The bar or strap 5 is provided with a lower slot 12 therein and with an upper slot 13, said upper slot being so cut in the material as to form an arm 14. 15 and 16 indicate slidable plates each of which is provided with depressions 17 pressed out of the metal to receive the anti-friction balls 18 which are supported in suitable depressions in the bar or strap as illustrated. The upper ends of the plates are bent inwardly into engagement with each other within the slot 90 13 and form a shoulder 19. 20 indicates a 95

compression spring encircling the arm 14, the upper ends of the plates 15 and 16 and bearing against the shoulder 19.

A bolt 20' extends through the slot 12 in the bar 5 and also through openings 21 in the plates 15 and 16. Said bolt is provided with ears 22 thereon received by slots 23 in the plate 15 whereby rotation of said bolt is prevented. The hub portion 24 of a lower rotatable sprocket 25 is mounted on the enlarged portion 26 of the bolt 20', a longitudinal movement of said sprocket on said portion 26 being prevented by a flange 27 on the end of said bolt and by an annular ridge 28 in the plate 15 pressed out of the metal. A nut 29 is screwed on the end of the bolt and holds the plates together in an obvious manner, a washer 30 preferably being interposed between the plate 16 and said nut. To prevent a rocking or turning movement of the sprocket on the bolt we have provided the plate 15 with two lugs or projections 31 pressed out of the metal on either side thereof which are adapted to contact with said bar 5 to prevent such rocking or turning movement.

An endless driving chain 32 passes over the upper sprocket 4 and the lower sprocket 25 and is held taut by the action of the spring 20 which, as hereinbefore described, presses downwardly against the vertically slidable member constituting the plates 15 and 16 and which carry the sprocket 25 therewith, thus preventing the chain from running off the sprockets as is manifest.

The chain 32 is connected to the window by means of a pin 33 engaging in a slot of a plate 34 secured to and depending from the window. By rotating a handle 35 connected to the upper sprocket 4 the chain is caused to travel around the sprockets 4 and 25 and the window is raised or lowered according to the direction of rotation given the handle. This portion of the construction of the device is old, however, and forms no part of the present invention.

What we claim as our invention is:—

1. In a window regulator, a bar provided with a beveled end, a wheel rotatably mounted thereon, a linear member running over said wheel for transmitting motion and a supporting member provided with a slot having a curved wall adjacent said slot, said slot loosely receiving the beveled end of said bar.

2. In a window regulator, a supporting bar, a wheel rotatably mounted thereon, a linear member running over said wheel for transmitting motion, a supporting bracket positioned to engage and support said bar, and means for guiding said bar into engagement with said bracket.

3. In a window regulator, a support provided with a slot therein, a sprocket, a chain extending over said sprocket for transmitting

motion, a bolt extending through said slot on which said sprocket is mounted, a plate slidable on said support and carried by said bolt and spring means engaging said support and said plate for tensioning 70 said chain.

4. In a window regulator, a support provided with a slot therein, a depression in said support, a sprocket, a chain extending over said sprocket for transmitting motion, 75 a bearing member receiving and supporting said sprocket and extending into said slot, a slide slidable on said support and secured to said bearing member, said slide having a depression therein corresponding with the depression in said support, and antifriction means mounted in said depressions.

5. In a window regulator, a bar provided with a slot therein, a sprocket, a chain extending over said sprocket for transmitting 85 motion, a bolt extending through said slot on which said sprocket is mounted, a slide comprising two plates carried by said bolt, means on said bolt for holding said plates in sliding engagement with said bar and 90 spring means engaging said slide for tensioning said chain.

6. In a window regulator, a support provided with upper and lower slots therein, a sprocket, a chain extending over said 95 sprocket for transmitting motion, a bolt extending through said lower slot on which said sprocket is mounted, a slide comprising two plates slidable on said support and carried by said bolt and having their ends bent 100 adjacent each other within said upper slot and a spring within said upper slot engaging said slide for tensioning said chain.

7. In a window regulator, a support provided with upper and lower slots therein, 105 an arm extending within said upper slot, a sprocket, a chain extending over said sprocket for transmitting motion, a bolt extending through said lower slot on which said sprocket is mounted, a slide comprising two plates slidable on said support and carried by said bolt and having their ends turned within said upper slot to form a shoulder and a spring within said upper slot supported by said arm and the ends of 115 said plates and bearing against said shoulder and adapted by its action to tension said chain.

8. In a window regulator, a bar provided with a slot therein, a sprocket, a chain extending over said sprocket for transmitting motion, a bolt extending through said slot on which said sprocket is mounted, a slide comprising a plate slidable on said bar and carried by said bolt, means on said bolt engaging said plate for preventing rotation of said bolt and spring means engaging said bar and said plate for tensioning said chain.

9. In a window regulator, a support provided with a slot therein and with an arm 120

extending within said slot, a slide comprising a plate slideable on said support and having a part extending within said slot, a wheel rotatably mounted on said slide, a linear member running over said wheel for transmitting motion and a spring encircling said arm and said part which extends with- in said slot for tensioning said linear member.

Signed at New York in the county of 10
New York and State of New York this 10th
day of January A. D. 1922
